Des. 228,708
Patented Oct. 23, 1973

228,708

SOFA

Henry Olko, Applegreen Drive,
Old Westbury, N.Y. 11568

Filed Jan. 11, 1972, Ser. No. 217,073

Term of patent 14 years

Int. Cl. D6—02

U.S. Cl. D6—57

Fig. 1

Fig. 2

Fig. 3

FIG. 1 is a perspective view of a sofa embodying my design.

FIG. 2 is a rear view of the sofa of FIG. 1; and,

FIG. 3 is an end elevation of one of the two identical ends of the sofa of FIG. 1.

I claim:

The ornamental design for a sofa, as shown and described.
